UNITED STATES PATENT OFFICE

2,559,541

COAL PUSHER

Eugene Martin, Wesleyville, Pa., assignor to Read Standard Corporation, a corporation of Delaware

Application December 11, 1946, Serial No. 715,495

9 Claims. (Cl. 198—224)

1

My invention relates to material pushing means and more particularly to appliances for mechanically pushing coal forward from the rear portion of the coal bin of a locomotive tender to place it within convenient reach of the fireman or to deliver it to the trough of the tender unit of a mechanical stoker.

An object of the present invention is to provide an improved coal pusher and operating mechanism therefor, so constructed and arranged in a tender to make it conveniently accessible; readily adaptable for application to tenders of different designs; so located as not to obstruct access to the coal bin; and arranged to be protected from injury by coal as the latter is loaded onto the tender.

Another object of the invention is to provide improved actuating means for a material pushing device, and more specifically improved hydraulic actuating means for a locomotive tender coal pusher including a fluid motor cylinder and piston housed in and operatively connected with the pusher element and fluid pressure generating and distributing means including a turbine, pump and fluid pressure distributing valve mounted outside the tender coal bin and connected through piping with the motor cylinder of the pusher element.

Another object of the invention is to provide a coal pusher that occupies a minimum of space in a tender fuel bin and that is effective over a maximum area of the rear slope sheet of the bin for pushing coal forward.

Another object of the invention is to provide improved means for automatically reversing the direction of movement of the pusher elements of a reciprocable material pushing appliance when the piston connected with the pusher element reaches the end of its stroke in the power cylinder.

Another object of the invention is to provide a novel and improved pusher unit embodying an actuating fluid cylinder and that is compact, durable and efficient in use, and in which the parts are readily accessible for repairs or replacement.

It has been customary in coal pushers for locomotive tender fuel bins to provide a plurality of pusher units operating concurrently irrespective of the extent to which the bin is filled. Thus when the bin is filled to the extent that all the pusher units are covered with coal, considerable power must be applied to move the pusher elements through the head of coal. It is, therefore, another object of this invention to provide a coal

2

pusher in which the load, particularly the static or starting load, on the motive power of the pusher is reduced when the coal in the bin covers all the pusher units. More specifically, the invention pertains to an improved coal pusher in which the rear pusher member may be rendered inoperative while the front pusher member operates to advance coal in the bin, and when the forward edge of the coal supply has receded to a point where the front pusher no longer moves an adequate amount of coal forward, the rear pusher unit may be placed in operation.

Another object of the invention is to provide improved distributing and automatic reverse valve mechanism for controlling the flow of the operating fluid to and from the power cylinders of the tender coal pusher units.

With these and other objects in view, the invention consists in the novel construction, arrangement and combination of parts, as will be understood from the preferred and practical embodiment of the invention hereinafter described and illustrated in the accompanying drawings, in which:

25 Figure 1 is a plan view of a portion of a locomotive tender with the novel coal pusher applied thereto, the cover for the cylinder housing of the rear pusher member being removed;

30 Figure 2 is a sectional view taken on the irregular line 2—2 of Figure 1 with a portion of the cylinder of the rear pusher member broken away;

Figure 3 is an enlarged sectional view taken on the irregular line 3—3 of Figure 1;

35 Figure 4 is an enlarged sectional view taken on the line 4—4 of Figure 1;

Figure 5 is a sectional view taken on the line 5—5 of Figure 2;

Figure 6 is a sectional view of the distributing and reverse valve mechanism taken on the line 6—6 of Figure 3;

40 Figure 7 is a sectional view of the distributing and reverse valve mechanism turned 90 degrees from the position shown in Figure 6; and

Figure 8 is a sectional view taken on the line 8—8 of Figure 7.

45 In the drawings the tender is shown as having the usual fuel bin 10, and the water compartment 11 located back of and beneath the same. The novel coal pusher is mounted in the tender and includes the pusher units 12 and 13 which are adapted to reciprocate over wearing plates 14 and 15, respectively, that overlie the slope sheet 16 of the tender. The pusher units 12 and 13 are similar in construction, so that in the following description, when describing the parts of one

pusher unit, it is to be understood that the description applies as well to the other pusher unit.

The pusher unit 12 comprises a central longitudinally extending housing 17 having side walls 18 and 19, a rear wall 20 and front wall 21, as best shown in Figures 2 and 4. A plurality of crossheads or pusher heads 22, 23 and 24 are formed with and project laterally from the housing 17 and function to push coal forwardly in the bin. The housing 17 of the pusher unit 12 is open at its bottom and top and is provided with a removable cover 25 forming a closure for the open top. The cover 25 is provided with a plurality of spaced transversely extending ribs or abutments 9 serving as auxiliary coal pushing means.

An operating cylinder 26 for the pusher unit 12 is disposed within the housing 17, the lower portion thereof preferably projecting through a longitudinal opening 27 formed in the rear slope sheet 16 and wearing plate 14, all as best shown in Figures 2 and 4. The wearing plate 15 and slope sheet 16 are provided with a similar opening 28 through which the operating cylinder of the pusher unit 13 projects. A well 29 formed by a longitudinally extending water tight casing 30 secured to the under side of the slope sheet 16 surrounds the openings 27 and 28 and forms a housing for the projecting portions of the cylinders and the piping to the cylinders. While the cylinders do not necessarily have to project through the openings 27 and 28, this construction is preferred since it permits reduction in the overall height of the housing 17 of pusher unit 12 and the similar housing of pusher unit 13.

Along each side of the opening 27 in the wearing plate 14 and slope sheet 16 extend superimposed spacer bars 31 and 32, the lower bars 31 being rigidly secured, as by welding, to the wearing plate 14. The cylinder 26 is rigidly secured in place by means of studs 33 that extend through the cylinder flanges 34, the upper spacer bars 32 and into the lower spacer bars 31. As shown in Figure 4, the upper spacer bars 32 project laterally outward a distance beyond the lower spacer bars 31, thereby forming a guideway for the flanges 35 formed with and extending inwardly of the lower edge of the sidewalls 18 and 19 of the cylinder housing 17. The spacer bars 31 and 32 thus form a guideway for the pusher unit 12 during its reciprocating movement and restrain movement of the pusher unit 12 away from the wearing plate 14.

The operating means for effecting reciprocating movement of the pusher unit 12 includes, in addition to the cylinder 26, removable rear and front cylinder heads 36 and 37, respectively, a piston head 38 fitted in the cylinder 26, and a piston rod 39 which is secured at one end to the piston head 38 and projects through a stuffing box 40 formed with the front cylinder head 37, the projecting end of the piston rod 39 being operatively connected to the front wall 21 of the pusher housing 17, in the manner to be described. A saddle 41 formed on the inner surface of the front wall 21 of housing 17 is provided with a semi-circular recessed seat 42. The seat 42 is arranged to receive a collar 43 secured to the forward end of the piston rod 39. Thus when the piston 38 and rod 39 move forward, the collar 43 pushes against the front wall 21 moving the pusher housing 17 forward across the wearing plate 14, and when the piston 38 and rod 40 move rearward, the collar 43 pushes against the lip 44 of the saddle 41 moving the pusher housing 17

rearward across the wearing plate 14. From the above description, it is evident that upon removal of the cover 25 and the bolts 33, the cylinder 26 and its associated parts can be inserted in or removed from the housing 17 of pusher unit 12 without dismantling other parts of the pusher device.

Fluid under pressure, preferably oil, for operating the piston 38 is supplied to the cylinder 26 of the pusher unit 12 through pipes 45 and 46 which serve alternately as intake and return lines to and from their respective sides of the piston 38. Similarly, the pipes 47 and 48 lead to the cylinder of the pusher unit 13, serving alternately as intake and return lines to and from their respective sides of the cylinder piston.

The oil reservoir 49, the motive power including the turbine 50 and pump 51, and the automatic operating and distributing valve 52 are mounted on the top wall 53 of the tank 11. Steam for operating the turbine is supplied from the locomotive boiler through intake pipe 54 and is exhausted from the turbine through pipe 55. The valve (not shown) for controlling the flow of steam to the turbine may be located in the locomotive cab or at some point in the tender conveniently accessible to the fireman. The turbine 50 operates the pump 51 which supplies fluid to the cylinders of the pusher units 12 and 13 for moving the pistons, the fluid behind the pistons returning to the reservoir 49. The pump 51 forces fluid from the reservoir 49 through the delivery pipe 56 to the intake port 57 of the distributing valve 52 and a return pipe 58 carries the fluid back to the reservoir 49 from the return port 59 of the valve 52.

A pair of lines 60 and 61 lead from the distributing valve 52 toward the cylinders of the pusher units 12 and 13, and function alternately as fluid supply and fluid return lines. The lines 60 and 61 are branched, respectively, at 62 and 63, as may be seen by referring to Figures 2 and 5. Line 60 branches into pipes 45 and 47 which, as previously stated, communicate respectively, with one side of the cylinder pistons of respective pusher units 12 and 13. Line 61 branches into pipes 46 and 48, which communicate, respectively, with the opposite side of the cylinder pistons of respective pusher units 12 and 13. In the pipes 45 and 46, which lead to the cylinder of the rear pusher unit 12, there is preferably interposed a cut-off valve 64 for interrupting the flow of fluid through the pipes 45 and 46, whereby the rear pusher unit 12 may be rendered inoperative while permitting continued operation of the front pusher unit 13. Any suitable means may be provided for operating the valve 64, that shown including a rod 65 extending transversely of the tender from the valve 64 to one side of the tender, and a rod 66 extending longitudinally of the tender to the forward end thereof, the rods 65 and 66 being connected by a bell crank lever 67. The forward end of the rod 66 is provided with a suitable operating handle (not shown) disposed for convenient manipulation by the fireman.

When both pusher units 12 and 13 are covered with coal, only the front pusher unit 13 need be operated in order to advance coal forwardly in the bin, and at such times the fireman may cut the rear pusher unit 12 out of operation in the manner and by the means described in the preceding paragraph. Then, when the forward edge of the coal supply has receded to a point where the front pusher unit 13 no longer moves an ade-

quate amount of coal forward, the fireman may place the rear pusher unit in operation.

Referring particularly to Figures 6, 7 and 8, the construction and operation of the distributing valve 52 which effects the alternate delivery of fluid to one side of the cylinder pistons of the pusher units 12 and 13 and the return of fluid from behind the pistons to the reservoir 49, will now be described in detail. The distributing valve 52 includes a cylinder 68 provided at its ends with removable heads 69 and 70, and a sliding hollow cylindrical valve member 71. As previously pointed out, the valve 52 is provided with an intake port 57 through which fluid from the reservoir 49 enters the valve 52, and a return port 59 through which fluid passes on its return to the reservoir 49. In addition to the ports 57 and 59, the valve 52 is provided with the ports 72 and 73 for the passage of fluid to and from the cylinders of the coal pusher units 12 and 13.

The opposite ends of the cylinder 68 are provided with ports 74 and 75 adapted to be opened or closed by the valve members 76 and 77, respectively. The valve members 76 and 77 are provided with stems 78 and 79, respectively, extending freely through transverse walls 80 and 81, respectively. The walls 80 and 81 form guides for the stems 78 and 79 and are provided, respectively, with a plurality of openings 82 and 83 for the passage of fluid. Springs 84 and 85 extend between the walls 80 and 81, respectively, and the valve members 76 and 77, respectively, and normally retain the valve members 76 and 77 in their seated positions to close the ports 74 and 75, respectively.

A passage 86 provides communication between the port 74 and a port 87 which opens into the cylinder 68 at a point intermediate its ends. A similar passage 88 provides communication between the port 75 and a port 89 which also opens into the cylinder 68 at a point intermediate its ends.

The sliding hollow cylindrical valve member 71 is provided with the three external annular cavities 90, 91 and 92 which are arranged to provide selective communication between various ports of the valve 52 in accordance with the position of the valve member 71. At its ends, cylindrical valve member 71 is provided with the central bosses 93 and 94 connected to the cylindrical wall thereof by the webs 95 and 96, respectively. The bosses 93 and 94 are arranged to contact the ends of respective stems 78 and 79 of respective valve members 76 and 77, whereby movement of the valve members 76 and 77 is transmitted to the cylindrical valve member 71.

In operation, with the cylindrical valve member 71 in the position as shown in Figures 6 and 7, pressure fluid from the pump 51 passes through pipe 56 and enters the distributing valve 52 through intake port 57. The stream of fluid after entering intake port 57 is divided, and one of the divided streams of fluid passes through port 97, the annular cavity 90 of the cylindrical valve member 71, as shown in Figure 7 and emerges from the distributing valve 52 through the port 73, as shown in Figure 6. At the same time the other of the divided streams of fluid passes through the passage 98, port 99, the annular cavity 92 of the cylindrical valve member 71, as shown in Figure 7, thence it passes through port 89, the passage 88 to the port 75, as shown in Figure 6.

The fluid emerging from port 73 passes through the pipe 61, then as previously described, through

the pipes 46 and 48, as shown in Figures 1 and 2, into the forward end of the cylinder 26 of pusher unit 12 and the similar cylinder of pusher unit 13. The pressure fluid entering the cylinders moves the piston 38 of pusher unit 12, see Figure 2, and the similar piston of pusher unit 13, rearwardly, thereby moving the pusher housing 17 of pusher unit 12 and the similar housing of pusher unit 13 rearwardly in the bin 10.

As the piston 38 and the similar piston of pusher unit 13 move rearwardly, the fluid at the rear of the pistons flows through the pipes 45 and 47, then through pipe 60 and enters the distributing valve 52 through port 72. The fluid then passes through the bore 100 of the cylindrical valve member 71, the port 101 of valve member 71, annular cavity 91 and emerges through port 59 into the pipe 58 and returns to the reservoir 49.

The piston 38 and the similar piston of pusher unit 13 having reached the end of their stroke, the increased pressure of the fluid resulting from continued operation of the pump 51 causes the valve member 77 to open against the pressure of spring 85. Movement of the valve member 77 is transmitted through the stem 79 to the cylindrical valve member 71, moving the latter to its extreme opposite position in the cylinder 68. In the latter position of the cylindrical valve member 71, flow of fluid through the passage 88 is cut off and escape of fluid through the ports 102 and 83 in the valve member 77 and transverse wall 81, respectively, relieves the pressure of the fluid in passage 88, thereby permitting the spring 85 to return the valve member 77 to its normal closed position.

Also in the latter position of the cylindrical valve member 71, it will be seen that the fluid entering the distributing valve 52 through port 57 is again divided into two streams, but the stream of fluid that passes through port 97 into the annular cavity 90, now emerges from the distributing valve 52 through the port 72 instead of the port 73, as in the previous position of the cylindrical valve member 71. At the same time the other of the divided streams of fluid passing through passage 98, port 99 and annular cavity 92, now emerges through port 87 and passes through passage 86 to the port 74 instead of emerging through port 89 and passing through passage 88 to the port 75.

The fluid emerging from port 72 passes through the pipe 60, then through the pipes 45 and 47, as shown in Figures 1 and 2, into the rearward end of the cylinder 26 of pusher unit 12 and the similar cylinder of pusher unit 13. The pressure fluid entering the cylinders moves the piston 38 of pusher unit 12 and the similar piston of pusher unit 13 forward, thereby moving the pusher housing 17 of pusher unit 12 and the similar housing of pusher unit 13 forward in the bin 10.

As the piston 38 and the similar piston of pusher unit 13 move forwardly, the fluid at the front of the pistons flows through the pipes 46 and 48, then through pipe 61 and enters the distributing valve 52 through port 73. The fluid then passes through annular cavity 91, the port 59, and pipe 58, and returns to the reservoir 49.

When the piston 38 and the similar piston of pusher unit 13 have reached the forward end of their stroke, fluid pressure will build up in the passage 86 causing the valve member 76 to open against the pressure of spring 84. Movement of the valve member 76 is transmitted

through the valve stem 78 to the cylindrical valve 71, moving the latter to its original position in the cylinder 68. On opening of the valve member 76, fluid escapes through the ports 103 and 82 in the valve member 76 and transverse wall 80, respectively, relieving the pressure of the fluid in passage 86, thereby permitting the spring 84 to return the valve member 76 to its normal closed position.

It is evident then, that the distributing valve 52 functions to automatically reverse the direction of movement of the pusher housing 17 of pusher unit 12 and the similar housing of pusher unit 13, when the pistons contained in their respective motor cylinders have reached the ends of their stroke in either forward or rearward direction as long as the turbine 50 and pump 51 are permitted to operate.

Referring to Figure 3, a relief valve 104 is preferably provided and is arranged to open at a predetermined pressure to permit fluid delivered by the pump 51 to pass through by-pass line 105 into the fluid return pipe 58 and back into the reservoir 49. Thus, if the pusher units 12 and 13 encounter some obstacle preventing their movement, or movement is impeded for any other reason, impairment of the pump and turbine is avoided.

Coal pushers in general use at present are operated by a reciprocating motor comprising a piston mounted in a cylinder to which steam is delivered from the locomotive boiler alternately to opposite sides of the piston. Since the steam pressure of the usual types of locomotives is between about 200 to 250 pounds, the cylinder for operating the coal pusher at that pressure is 15 inches or more in diameter. In my improved hydraulic coal pusher, employing a pump capable of developing about 1,000 pounds pressure, a pusher operating cylinder of about 6 $\frac{3}{4}$ inches in diameter may be employed. These figures are merely illustrative and a smaller or larger diameter cylinder may be used depending on the pressure developed by the pump selected.

It is evident then, that using the same source of steam, a relatively small size cylinder may be employed in my hydraulic operated pusher as compared with the conventional cylinder employed in present steam cylinder operated pushers, thus encroaching less on the coal space in the tender bin.

While in the preferred form of my invention as illustrated in the drawings and described above, the cylinder for operating the pushers is mounted in a housing within the pusher units, it is apparent that the cylinder may be mounted on the upper end of the slope sheet and its piston rod operatively connected with a pusher member or a plurality of connected pusher members as shown in Patent No. 1,747,899 issued February 18, 1930 to F. Hogg.

I claim:

1. A coal pusher for a locomotive tender fuel bin, including a coal pushing member mounted for reciprocation over a fuel supporting wall of said bin, a hydraulic fluid pressure operated motor cylinder for actuating said pushing member and mounted in said pushing member, a source of hydraulic fluid pressure mounted on the tender without said bin, and means forming a hydraulic circuit with said source and said cylinder.

2. A coal pusher for a locomotive tender fuel bin, including a pushing member mounted for reciprocation over a fuel supporting wall of said

bin, a fluid pressure operated motor cylinder for actuating said pusher member, said cylinder being housed in said pushing member, a source of fluid pressure mounted on the tender without said bin, and means connecting said source of fluid pressure with said motor cylinder.

3. A coal pusher for a locomotive tender fuel bin, said bin having a slotted fuel supporting wall and a casing on the underside of said wall embracing the slotted portion thereof, a pushing member mounted for reciprocation over said wall, a fluid pressure operated motor cylinder for actuating said pushing member, said cylinder being housed in said pushing member, a source of fluid pressure mounted on the tender without said bin, and means extending through said casing and slotted wall connecting said source of fluid pressure with said motor cylinder.

4. A coal pusher adapted to be mounted on the tender of a locomotive, comprising a pusher member mounted for reciprocation in the bin of said tender, means for operating said pusher member including a hydraulic cylinder mounted in said pusher member, a piston mounted for reciprocation within said cylinder, a connection between said piston and said pusher member for transmitting reciprocating motion thereto, a pump, means forming a hydraulic circuit with said pump and cylinder, valve mechanism in said circuit for controlling the flow of hydraulic fluid to and from the opposite sides of said piston for effecting reciprocating movement thereof, and means for operating said pump.

5. A coal pusher adapted to be mounted on the tender of a locomotive, comprising a plurality of pusher members mounted for reciprocation in the bin of said tender, means for operating said pusher members including a hydraulic cylinder mounted in each of said pusher members, a piston mounted in each of said cylinders for reciprocation therein, a connection between each of said pistons and a respective pusher member for transmitting reciprocating motion thereto, a pump, means forming a hydraulic circuit with said pump and said cylinders, valve mechanism in said circuit for controlling the flow of hydraulic fluid to and from the opposite sides of said pistons for effecting reciprocating movement thereof, and means for operating said pump.

6. A material pushing device including a housing and pusher members projecting laterally from said housing, said housing and pusher members being adapted to reciprocate over a material supporting wall, a motor cylinder in said housing stationarily mounted with respect to said supporting wall, a piston mounted for reciprocation within said cylinder, a connection between said piston and said housing for transmitting reciprocating motion from said piston to said housing, and means for alternately supplying pressure fluid to and exhausting pressure fluid from the opposite ends of said cylinder for operating said piston.

7. A material pushing device including a housing and pusher members projecting laterally from said housing, said housing and pusher members being adapted to reciprocate over a material supporting wall, a motor cylinder in said housing stationarily mounted with respect to said supporting wall, a piston mounted for reciprocation within said cylinder, a connection between said piston and said housing for transmitting reciprocating motion from said piston to said housing, a fluid circuit for conducting

fluid to and from each end of said cylinder, and a valve in said circuit for alternately reversing the direction of flow of fluid in said circuit at the end of each stroke of said piston.

8. A material pushing device comprising a housing adapted to receive means for actuating said pushing device, said housing having side walls and an open top and bottom, a removable cover for said open top, said cover having raised transversely extending pushing abutments, and a plurality of pusher members projecting laterally from said housing.

9. A material pushing device comprising a housing, pusher members projecting laterally from said housing, said housing and pusher members being adapted to reciprocate over a material supporting surface, a fluid motor cylinder in said housing stationarily mounted with respect to the supporting wall, a piston mounted for reciprocation in said cylinder, a connection between 20 said piston and said housing for transmitting

5

reciprocating movement from the piston to the housing, and means to supply operating fluid to said cylinder.

EUGENE MARTIN.
